HAND LAMP

Raymond B. Van Sickles, New Haven, Conn., assignor to Winchester Repeating Arms Company, a corporation of Maryland

Application May 26, 1933, Serial No. 672,953

2 Claims. (Cl. 240—10.63)

This invention relates to hand lamps and more particularly to a hand lamp having means whereby light rays from a single source may be projected from the hand lamp casing in two opposite directions.

In carrying out my invention, I provide a hand lamp casing adapted to receive dry cells and having suitable electrical connections to complete a circuit to a lamp bulb in the casing. I further provide an opening in the front of the casing with a reflector arranged behind the opening, said reflector having a lamp socket therein for the reception of the lamp bulb. The casing is also provided with one or more openings in its rear wall and the reflector is provided with suitable openings through which pass a portion of the rays from the lamp. A rear reflector is arranged in the casing to direct this portion of the rays of light through a rear opening or openings.

The lamp so constructed provides a device which may be employed as a searchlight to direct an ordinary beam of light forwardly and the rear openings may be provided with red lenses to act as a rear signal light.

In the accompanying drawing I have shown one form of the invention. In the drawing:

Fig. 1 is a rear elevation;

Fig. 2 is a vertical, sectional view substantially on the line 2—2 of Fig. 3;

Fig. 3 is a vertical, sectional view at right angles to Fig. 2;

Fig. 4 is a horizontal, sectional view through the upper part of the casing on the line 4—4 of Fig. 2; and

Fig. 5 is a similar view through the lower portion of the casing on the line 5—5 of Fig. 3.

Referring to the drawing, the reference numeral 1 designates generally a casing which is shown rectangular in cross section but which may be of any desired shape. The casing consists of two sections. The main portion of the casing comprises a back wall 2, side walls 3, a top 4 and a bottom 5. The front 6 of the casing is removable to permit access to the interior. As shown, it is provided with a flange 7 adapted to fit over the adjacent side walls, top and bottom. The bottom of this flange is provided with a pair of upstanding lugs 8 adapted to be received in openings 9 in the bottom of the main portion of the casing. The top flange is provided with an ear 10 having an opening therein adapted to receive a pin 11 on the top of the casing. A bail 12 may be pivotally mounted on the top 55 of the casing by arranging the ends of the bail in sleeves 13 mounted on the top.

The front wall 6 of the casing is provided with an opening 14 and the wall surrounding this opening may be projected forwardly as at 15 and provided with a retaining flange 16. A lens

17 is arranged in the opening and a reflector 18 is arranged behind the lens. The lens and reflector may be retained in position by means of spring clips 19 secured to the inner side of the wall 6. A lamp socket 20 is carried by the reflector, preferably being formed therein in the conventional manner, and a lamp bulb 21 is adapted to be mounted therein. This construction electrically connects one terminal of the lamp bulb to the casing, which may be made of metal, in the conventional manner. A spring contact 22 is adapted to engage the base terminal of the lamp bulb when the parts are in position. This spring terminal is carried by a plate 23, preferably formed integral therewith. The plate 15 is mounted on the front of an insulating board 24 which may be made of fibre-board or other suitable material, and which is arranged in the casing and is substantially coextensive in size with the casing. The plate 23 is secured to the 20 insulating board by rivets 25, or in any other suitable manner, and one of these rivets forms an electrical connection between the plate and a conducting strip 26 arranged on the back of the insulating board. The other end of the conducting strip is electrically connected to a contact clip 27 mounted on the front of the insulating board and arranged in the lower portion of the casing. This contact clip carries a spring arm 28 which projects forwardly in the casing 30 and forms a spring support for one end of a dry cell. A similar contact clip 29 is arranged beneath the contact clip 27 and likewise carries a spring arm 30 which is adapted to engage a terminal of a dry cell. The arms 28 and 30 are 35 properly spaced from each other to receive the terminals of two adjacent cells 31 and 32.

The opposite ends of cells 31 and 32 are supported by a contact clip 33 which is also carried on the front of the insulating board 24 and this contact clip carries a forwardly projecting arm 34 having a cross arm 35 at its end, the ends 36 of the cross arm being spaced and shaped to receive the opposite terminals of the cells 30 and 31. It will thus be seen that when a pair of dry 40 cells are arranged in the contact clips the circuit which extends from the base terminal of the lamp bulb to the upper contact clip 27 is completed through the cells to the lower contact clip 29.

A second conducting strip 37 is arranged on the back of the insulating board and is electrically connected to the contact clip 29 by one of the rivets 38 which secures the two members to each other. This contact strip extends upwardly to a point adjacent the top of the casing and is electrically connected to a contact member 39 on the front of the insulating board, which member is provided with an outwardly projecting contact 40 extending forwardly just beneath the 50 55 60

top of the casing. Suitable switch means is provided on the top of the casing to form a connection with the contact 40 and thus complete the circuit. The top of the casing is provided with 5 a slot and an operating switch member 41 is mounted on the exterior of the top of the casing adjacent this slot. A contact member 42 is arranged within the casing and connected to the operating switch member by rivets 43 which 10 extend through this slot. As shown, the end of the movable contact member 42 is curled or extended downwardly from the end of the casing to insure contact with the stationary contact 40.

To insulate the conducting strips and contact 15 clips from the casing, I provide a sheet of insulation which may be formed of cardboard or other suitable material and which covers the back of the casing as indicated at 45. This sheet is also provided with side flaps 46 in the lower part of 20 the casing to insulate the contact clips 27, 29 and 33 from the side walls of the casing and is further provided with an upper flap 47 to insulate the spring contact clip 22 and a portion of the contact 39 from the top of the casing. The upper flap, however, is cut away adjacent the engaging 25 end of contact 40 to permit it to engage the slideable contact 44. The insulating member may also be provided with a bottom flap 48 to insulate the bottom cell 32 from the bottom of the 30 casing. The cell is generally provided with a wrapping of insulating material but the bottom flap 48 insures insulation from the casing in case this wrapping should become worn.

The means whereby a beam of light may be 35 projected rearwardly from the bulb 21 in addition to the beam of light projected forwardly through the lens 17 consists of suitable openings 49 in the reflector 18 by means of which a portion of the rays of light are permitted to pass through 40 the reflector toward the side walls of the casing. The rear wall of the casing is provided with openings 50 in horizontal alignment with the openings 49 in the reflector and the material of the casing surrounding these openings may be shaped outwardly as at 51 to form flanges to receive lenses 52. These lenses 52 may be made of red glass if 45 desired. To direct the rays of light passing through the openings 49 to the openings 50 I provide reflectors in the form of clips 53 secured to the side walls of the casing and having parts 54 projecting toward the reflector. The rear surfaces of these spring clips may be polished to 50 form the rear reflectors.

A clip 55 may be arranged on the back of the 55 casing, this clip being provided with a bolt 56 extending through it and a wing nut 57 whereby it may be clamped on any suitable support.

The insulating board 24 and the cardboard

insulating member 45 which is arranged behind it are arranged with suitable openings in alignment with the rear openings 50 of the casing to permit the rays of light to be projected through the lenses 52.

The operation of the device will be apparent from the foregoing description. The circuit through the lamp bulb is completed when the slideable contact 44 on the under side of the top 10 of the casing is moved into engagement with the contact 40. This lights the bulb 21 and rays of light are projected through the lens 17 in the front of the casing in the usual manner. A portion of the rays of light also pass through the 15 openings 49 in the reflector 18 and strike the reflecting surfaces of the rear reflectors 54. These rays of light are directed through the openings 50 and the lenses 52.

I claim:

1. A hand lamp comprising a casing having a front wall, a rear wall and side walls, the front wall of said casing being provided with an opening, a main reflector arranged therein, a lamp socket carried by said reflector, a lamp bulb arranged in said socket, a battery arranged in said casing, means for electrically connecting said bulb to said battery, said main reflector being provided with an opening, the rear of said casing being provided with an opening, and a clip secured to one of the side walls of said casing and having a portion thereof extending at an angle toward said reflector, the surface of said clip forming a rear reflector to project rays of light passing through said opening in said main reflector through the rear opening in the casing substantially parallel to the rays of light projected through the front opening of said casing.

2. A hand lamp comprising a casing having a front wall, a rear wall and side walls, the front wall of said casing being provided with an opening, a main reflector arranged therein, a lamp socket carried by said reflector, a lamp bulb arranged in said socket, a battery arranged in said casing, means for electrically connecting said bulb to said battery, said main reflector being provided with an opening adjacent said lamp socket and positioned to permit passage of rays of light therethrough substantially at right angles to the direction of the rays of light projected through said opening in the front wall of said casing, the rear of said casing being provided with an opening, and a clip secured to one of the side walls of said casing and extended at an angle toward said reflector, the surface of said clip forming a rear reflector to project rays of light passing through the opening in said main reflector through the rear opening of said casing.

RAYMOND B. VAN SICKLES.
